UNITED STATES PATENT OFFICE.

CHARLES G. SUTHERLAND, OF BALTIMORE, MARYLAND.

SEAT-COVER FOR WATER-CLOSETS, &c.

No. 920,213.

Specification of Letters Patent.

Patented May 4, 1909.

Application filed March 26, 1908. Serial No. 423,414.

To all whom it may concern:

Be it known that I, CHARLES G. SUTHERLAND, a citizen of the Dominion of Canada, residing at Baltimore city, in the State of Maryland, have invented certain new and useful Improvements in Seat-Covers for Water-Closets and the Like, of which the following is a specification.

This invention relates to seat covers for water closets and the like, and its primary object is to provide simple and efficient means for the prevention of the spread of disease or vermin through the use by persons of water closets in public places such as for example as hotels, railway stations and the like.

A further object of the said invention is the provision of a seat cover for the above purpose which shall be simple, inexpensive, easily placed on and removed from the seat, and one which will stay in position on the seat as long as this is desired, without the use of extra retaining devices outside of the cover itself.

With the above ends in view my said invention consists in the novel structure herein described and more particularly pointed out in the accompanying claims.

In order to more fully describe my said invention reference will be had to the accompanying drawings, wherein the same parts are indicated by similar numerals throughout the several views, and wherein,

Figure 1, represents in perspective a water closet seat provided with a form of my improved cover; Fig. 2, a perspective view of said cover removed from the seat, and Fig. 3, an enlarged section taken along line 3-3 Fig. 2.

As illustrated in the accompanying drawing my improved seat cover comprises a body portion 1 of cloth, paper or other suitable material provided with an opening 2 to register with the opening in the seat.

Around this opening 2 extends an annular apron 3 made fast to the body portion 1 in any suitable way, the said apron being adapted to extend downward into the seat opening.

Around the outer edge of and made fast to the body portion 1 is an apron 4 adapted to extend downward over the outer edge of the seat.

The apron 4 terminates on each side of the seat near the rear thereof, and between

its ends the body portion 1 forms a flap 5 adapted to extend across the rear of the seat.

If the seat cover is made of textile fabric, the aprons 3 and 4 are preferably stitched to the main body portion 1; if of paper, they may be pasted on said body portion, or, these aprons may be formed in any other suitable way.

The aprons 3 and 4 perform the two fold function of providing a protecting covering around the edges of the seat and providing retaining means which will effectually hold the cover in position on the seat, preventing the same from rising up or slipping from side to side.

Devices of this character if made of textile fabric may be readily removed for washing and replaced by clean ones. If made of tissue paper they may be folded into very small packages and dispensed to users.

In the accompanying claims I use the term "fabric" in its generic sense to include not only textile fabric, but paper of any kind.

Having thus described my invention what I claim is:

1. A seat cover for water closets and the like, comprising a fabric body portion to rest upon the top of the seat and having an opening to register with the opening in the seat, provided with two substantially concentric aprons, one arranged to extend around said opening and downward into the seat opening, and the other around the outer edge of said body portion arranged to extend downward over the outer edge of the seat around the front and sides thereof said aprons extending in a direction substantially at right angles to the body of the cover and adapted by their engagement with the outer and inner edges respectively of the seat to hold said cover in position on said seat independently of other retaining means, each of said covers constituting a single unit, substantially as described.

2. A seat cover for water closets and the like, comprising a fabric body portion to rest upon the top of the seat and having an opening to register with the opening in the seat an annular apron comprising a strip of fabric secured to the said body portion around the edge of said opening therein and adapted to extend downward into the opening in said seat, and an apron comprising a strip of fabric secured to said body

portion around its outer edge and adapted to extend over the outer edge of the seat around the front and sides thereof, the said body portion terminating at its rear in a flap formed between the ends of the outer apron said aprons extending in a direction substantially at right angles to the body of the cover and adapted by their engagement with the outer and inner edges respectively of the

seat to hold said cover in position on said seat independently of other retaining means, each of said covers constituting a single unit.

In testimony whereof I affix my signature in presence of two witnesses.

CHARLES G. SUTHERLAND.
